ATTORNEYS

UNITED STATES PATENT OFFICE

DANIEL E. STAIR, OF HUDSON, NEW YORK, ASSIGNOR TO GIFFORD-WOOD COMPANY, OF HUDSON, NEW YORK, A CORPORATION OF NEW YORK

COVER FOR STORAGE BINS

Application filed October 12, 1928. Serial No. 312,100.

This invention relates to covers for storage bins and the like and, among other objects, aims to provide an improved hatchway cover installation adapted to protect the contents 5 of the bins from the weather and yet permit dumping of material into the bins.

In the drawings:

Fig. 1 is a plan view showing one embodiment of the invention applied to a series of 10 storage bins, one of the covers being shown in open position;

Fig. 2 is a vertical longitudinal section through the same;

Fig. 3 is a similar view, drawn on an enlarged scale; and

Fig. 4 is a transverse sectional view taken on the line 4—4 of Fig. 3, and on the same scale.

Referring particularly to the drawings, an 20 illustrative cover installation is shown as being applied to a series of storage bins 10 on top of which is mounted a trackway 11. The trackway 11 is herein shown as being supported on spaced beams 12 extending 25 longitudinally of the series of bins. A traversing hoist carrying a hoist bucket (not shown) is adapted to travel on the trackway 11 and is operated so as to stop over one of the bins while the bucket is lowered therein 30 for dumping.

An installation of the type indicated is particularly useful in handling heavy, bulky materials, such as sand, gravel, coal and the like. In wet or cold weather, such materials 35 must be protected from rain or snow; otherwise they will become wet and will freeze and cannot be taken from the bins. According to the present invention, hatchways are provided in the roofs of a series of bins and 40 weatherproof closures for the hatchways are arranged to be selectively opened to permit the bins to be filled, and after a bin is filled, the closures may move by gravity to close the hatchways.

Herein, the hatchways are located substantially at the centers of the bins and are defined by beams 12 and cross beams 13 connected between the beams 12. Inclined roof portions 14 are arranged longitudinally of the 45 battery of bins along the outer sides of the

beams 12 and extend from the beams 12 to a point beyond the rims of the bins. Additional inclined roof portions 15 are located between the beams 12 and extend from the beams 13 to a point between adjacent bins.

The closure herein comprises a cover 16 of a width preferably equal to the distance between the beams 12 and slightly longer than the distance between the beams 13 so that the cover overlaps the opening. The cover is 55 shown as being supported on rollers 17, carried by axles 18 connected to the underside of the platform by suitable brackets 19. The covers are adapted to roll on trackways, herein formed of angle irons 20 secured to the 60 beams 12, and in order that each cover may gravitate to close its hatchway, and open without interfering with the adjacent cover, the tracks 20 are inclined, as clearly shown 65 in Figs. 2 and 3. The lower ends of the 70 tracks are substantially flush with the bottoms of the beams 12 and their upper ends overlie the lower ends of the trackways for the adjacent bin cover (see Fig. 3) and are spaced above the same a distance greater 75 than the height of a cover, so that any cover may be opened without interference.

To enable an operator on the ground to open any selected cover, a series of ropes or cables 21 are secured to the respective covers, 80 each cable being preferably secured to the lower end of its cover on the underside (Fig. 3) and reeved over a sheave 22 mounted on the roof 15 at the rim of the corresponding bin, so that the cable may then pass downwardly between adjacent bins. The lower 85 end of the cable is located within reach of an attendant who may be on the ground or in the machine house (not shown) where the trolley bucket is controlled. It will be clear 90 that when the cable is pulled downwardly, the cover will roll up the incline.

In order that any cover may be held open, a ring or loop 23 is provided on each cable and is adapted to be caught under a hook or 95 cleat 24 (see Fig. 2). When the hatchway is to be closed, the ring 23 is released from the hook 24 and the cover will roll down the trackway by gravity.

A depending flange 25 secured to the upper 100

end of each cover projects downwardly in close proximity to the roof to prevent water, etc. from entering that end of the hatchway when the cover is closed. The lower end of the cover plate overlies the roof and protects the other end when the cover is closed.

From the foregoing description it will be seen that the covers may be selectively opened by remote control means and will close by gravity upon being released. Moreover, the operator of a tram car is relieved of this work. Further, such installations may be made at a low cost on old bins without necessitating extensive alterations.

Obviously, the present invention is not restricted to the particular embodiment thereof herein shown and described.

What is claimed is:

1. In combination with a plurality of storage bins having hatchways therein; an inclined trackway associated with each hatchway, the upper ends of each trackway overlapping the lower ends of the adjacent trackway; and a movable cover for each hatchway mounted to travel on the trackway to permit the cover to close by gravity.

2. In combination with a plurality of storage bins having hatchways therein; an inclined trackway associated with each hatchway, the upper ends of each trackway overlapping the lower ends of the adjacent trackway; a cover for each hatchway; rollers mounted on each cover and adapted to travel on the trackway to permit the cover to close by gravity; a stationary pulley associated with each cover; and a cable connected to the cover and passing over the pulley to permit the cover to be opened from the ground.

3. In combination with a plurality of storage bins having hatchways therein, an inclined trackway associated with each hatchway, the upper ends of each trackway overlapping the lower ends of the adjacent trackway; a cover for each hatchway; rollers mounted on each cover and adapted to travel on the trackway to permit the cover to close by gravity; a stationary pulley associated with each cover; a cable connected to the cover and passing over the pulley to permit the cover to be opened from the ground; and means to retain the cover in open position.

In testimony, that I claim the foregoing as my own, I have hereto affixed my signature.

DANIEL E. STAIR.
